UNITED STATES PATENT OFFICE.

ROBERT V. HOWES, OF BROOKLYN, NEW YORK.

GAS-BURNER.

1,283,776.

Specification of Letters Patent.

Patented Nov. 5, 1918.

Application filed May 10, 1918. Serial No. 233,703.

To all whom it may concern:

Be it known that I, ROBERT V. HOWES, a citizen of the United States, and a resident of the city of New York, borough of Brooklyn, in the county of Kings and State of New York, have invented a new and Improved Gas-Burner, of which the following is a full, clear, and exact description.

This invention relates to burners and has for an object the provision of an improved construction which may be used in any stove or range or other appliance especially constructed for burning coal, gas, wood, or oil.

Another object of the invention is the provision of a gas burning structure wherein a heat absorbing body is provided and formed so as to loosely accommodate gas pipes whereby air surrounding the pipes may be heated before being discharged adjacent the end of the pipe carrying the flame.

A still further object of the invention is the provision of a gas burner using a combustion mixture and certain arrangement of pipes and heat retaining material whereby an auxiliary supply of heated air is provided adjacent the supply or mixture of air and gas so that a maximum combustion is secured and consequently a maximum heat procured from a given volume of gas.

In the accompanying drawings:

Figure 1 is a longitudinal vertical section through an ordinary coal burning stove, with an embodiment of the invention shown applied thereto.

Fig. 2 is a sectional view on a slightly enlarged scale through Fig. 1 on line 2—2.

Fig. 3 is a top plan view of a burner embodying the invention the same being partially broken away for illustrating certain parts of the construction.

Fig. 4 is a transverse sectional view through Fig. 3 on line 4—4.

Fig. 5 is a detail fragmentary sectional view similar to Fig. 4, but showing a slightly modified form of the invention.

Referring to the accompanying drawings by numerals, 1 indicates a stove of any desired kind, as for instance an ordinary kitchen range designed for using wood or coal as fuel. The stove has naturally a smoke pipe 2 connected therewith so as to remove the smoke and unburnt gases from the fire chamber 3. A grate 4 is arranged at the bottom of the fire chamber 3, said grate being of any desired or usual structure for supporting wood, coal, or any desired fuel.

Arranged in the fire chamber 3 is a burner 5 embodying the invention which utilizes gas as fuel for heating the stove 1. This burner, as shown more particularly in Figs. 2 to 4 60 inclusive, is provided with a body 6 formed preferably in a solid block and provided with a number of apertures 7. The material of which the block 6 is made may vary as desired, as for instance a refractory material 65 may be used, fire-brick being especially desirable as preferably some form of material is used which will absorb heat and thereby raise the temperature of the air passing through the openings or passageways 7. 70 Passageways 7 may be arranged in any desired order, as for instance in rows as shown in Fig. 2. In each of these passageways is arranged a pipe 8 of any suitable material, as for instance metal. All of the pipes 8 75 of a single row are preferably connected to an auxiliary header 9 as shown in Fig. 4. The various headers 9 are connected to the main or principal header 10 by pipes 11, there being one pipe 11 for each header 9. 80 An air mixer 12, is provided for each of the pipes 11, as well as the valve 13. In mounting the tubes or pipes 8 in the passageways 7 the parts are so proportioned that there will be an appreciable air space around the pipes, 85 and said pipes are also of such a length as to fall short somewhat of the upper surface of the block 6 as shown in Fig. 2. During the operation of the burner air will pass upwardly through the passageways 7 and 90 mix with the gas emerging from the pipes 8, said air moving somewhat as a hollow column so as to, in a certain sense, surround the flame at the lower end and thereby provide an exceptionally good mixture. 95

During the more or less continuous use of the burner heat will be absorbed by the block 6 and consequently the air in the passageways 7 will be heated so that air at a comparatively high temperature will be supplied 100 to the gas as it passes through pipes 8. The heating of the air will cause an updraft so that the air will be supplied to the gas at some appreciable pressure and thereby produce an extremely hot and intense flame 105 having a higher flame temperature than the ordinary atmospheric burner, while at the same time producing perfect combustion with a smaller percentage of excess air than is ordinarily necessary. The thickness of 110 the block 6 may vary as occasion may demand, but is preferably of some appreciable

thickness so as to provide as long a passageway 7 as possible. The block 6 may be supported in any suitable way, but is preferably provided on the bottom with a metal plate 14 to which suitable angle irons 15 are connected, said angle irons in turn being connected to a number of supporting upright plates 16. The plates 16 at the bottom are connected to the angle irons 17 and 18, which angle irons are connected in any suitable manner with the block 19, which block is formed from refractory material, or any desired material. Block 19 is designed to rest upon the grate 4 or other suitable support and may be solid as shown, or may be provided with apertures 19' as shown in Fig. 5, so that air may enter from the bottom into the open space 20, or from the sides and ends into said open space. The open space 20 is supplied with air from the usual ash pit of the stove 1 and said air passes up through the passageways 7 as the secondary air while the primary air is taken in at the various mixers 12. This arrangement of air-inlet and associate parts permits any one mixer and any one row of pipes 8 to be used so that all of the pipes could be used at full capacity or partial capacity, or any one row may be used whereby there is great flexibility in the control of the heat produced.

What I claim is:

1. A gas burner comprising a block, a plurality of apertures therein, a gas pipe fitting into each of said apertures, but not filling the apertures, a supply pipe for supplying gas to said first mentioned pipes, and an air mixer for mixing air with the gas passing through said supply pipe whereby said first mentioned pipes will discharge a mixture of air and gas, and the apertures in which the first mentioned pipes are positioned will supply secondary air.
2. A gas burner comprising a block of non-combustible material having a plurality of apertures extending therethrough, a pipe fitting into each of said apertures extending

from the bottom to near the top, said pipes being of a less diameter than said apertures, a supply pipe for the first mentioned pipes, 50 an air and gas mixer connected with said supply pipe, and means directing a supply of gas to said air and gas mixer.

3. A gas burner for coal burning stoves comprising a body fitting into the fire chamber of the stove, said body having a plurality of passageways extending vertically therethrough, a gas pipe arranged in each of said passageways, extending from the bottom upwardly to near the top of the body, 60 said gas pipes being arranged in series, an auxiliary header for each series of pipes, an independent supply pipe for each header, an air and gas mixer for said supply pipes, means for supplying gas to said mixers 65 under pressure and a valve for each mixer positioned between the means for supplying gas and the respective mixers, said first mentioned pipes being of less diameter than the apertures in which they are positioned, 70 whereby as the mixture of air and gas from said mixers passes through said pipes air will pass around said pipes and be discharged in a substantially tubular sheet from said body.

4. A gas burner comprising a solid block of refractory material having a plurality of series of passageways extending from the bottom to the top whereby when the block is heated the air in said passageways will move 80 with some appreciable speed therethrough, a gas pipe arranged in each of said passageways extending from below the bottom to near the top, each of said gas pipes falling short of the top, an auxiliary header for the 85 gas pipes of each series of passageways, a supply pipe connected to each of said headers whereby any series of gas pipes may be provided with gas, an air mixer connected with each of said supply pipes, and means to 90 supply gas under pressure to each of said air mixers.

ROBERT V. HOWES.
